[57] CLAIM

The ornamental design for a razor blade scraper, as shown.

DESCRIPTION

FIG. 1 is a top plan view of a razor blade scraper in a retracted position;

FIG. 2 is a bottom plan view thereof;

FIG. 3 is a left-hand side elevational view thereof;

FIG. 4 is a right-hand side elevational view thereof;

FIG. 5 is a front elevational view thereof;

FIG. 6 is a rear elevational view;

FIG. 7 is a top plan view of the razor blade scraper in its extended position;

FIG. 8 is a bottom plan view thereof;

FIG. 9 is a right-hand side elevational view thereof;

FIG. 10 is a left-hand side elevational view thereof;

FIG. 11 is a front elevation view thereof; and,

FIG. 12 is a rear elevation view thereof.

The broken line showing the razor blade is for illustrative purposes only and forms no part of the claimed design.
